AUTOMATIC SYRINGE INJECTOR

Fairleigh S. Dickinson, Rutherford, N. J.

Application January 30, 1935, Serial No. 4,009

18 Claims. (Cl. 128—215)

This invention relates to automatic syringe injectors and more particularly to an automatic injector which is intended for use with a syringe for hypodermic and intra-muscular injections whereby the needle on such syringe may be automatically inserted into the body of the patient to the proper depth of penetration. The object of the invention is to improve the structure of such syringe injectors so as to make them more efficient and reliable.

Automatic injectors of the indicated type usually comprise a holder for an especially constructed or ordinary hypodermic syringe which when released from a set position is plunged downwardly under the action of a spring so as to cause the needle of the syringe to pierce the skin of the patient and project into the fleshy area to be treated. In all such devices, the spring must be sufficiently powerful to effect a rapid plunging action of the needle. Injectors of this type are also usually provided with a regulator for controlling the depth of penetration of the needle thereby making it possible for the patient himself or any lay person to properly inject a medicament into the area to be treated. Because of the above mentioned advantages, such syringe injectors are being used to an increasing extent by individual lay users of insulin. Existing syringes of this type have in common, however, certain disadvantages which it has become increasingly important to remove in view of the increasing use of such syringes by lay users so that the mechanism shall function in a most reliable fashion as to all of its several functions. The chief disadvantage of the existing syringes, is the fact that the needle vibrates considerably in entering the flesh of the patient. In studying the cause of this unsatisfactory condition, I have found that the cause of the excessive vibration of the needle lay primarily in the fact that the vibrations which were developed in the support for the syringe as a result of the swift plunging action of the parts were too definitely transmitted to the syringe and thence to the needle point. The sudden abrupt stopping of the swift plunging action of the needle at the end of its stroke was also a contributing cause, though to a much lesser extent. Those prior syringe injectors in which the syringe holder is encased within an outer cylinder possessed in addition the disadvantage that the graduation marks on the syringe barrel were, so far as I am aware, almost entirely covered when the syringe was in its normal or projected position so that the user of one of such prior devices never knew for a certainty

whether he was injecting the proper dosage of the medicant into the penetrated flesh.

The purpose of the present invention is to provide an improved automatic syringe injector construction which will overcome all the above mentioned and other difficulties and particularly to provide simple, sturdy and satisfactory means which will minimize vibration of the syringe in its downward plunging motion, will guide the needle straight to the point where the medicament is to be injected and will minimize vibration of the needle in the flesh of the patient. A further object of the invention is to provide an automatic syringe injector of the stated type in which the parts are so arranged that the scale on the syringe barrel can be easily read when the syringe is in its downward or projected position.

Other objects and advantages of the invention will become apparent from the following description, taken in connection with the accompanying drawings in which I have shown for the purposes of illustration, the preferred embodiment of my invention. In these drawings, Fig. 1 is a side elevation of the device showing the parts in normal or projected position; Fig. 2 is a front elevation of the device partly in section, with the parts set to project the syringe needle; Fig. 3 is a rear elevation of the device showing the relation of the parts in normal position; Fig. 4 is a central vertical section of Fig. 1, the syringe, however being shown in side elevation; Fig. 5 is a view taken along line 5—5 of Fig. 4; Fig. 6 is a section taken along line 6—6 of Fig. 4; Fig. 7 is a view similar to Fig. 5 showing the cap rotated through 90° so that the syringe may be removed from its supporting casing; Fig. 8 is a section similar to Fig. 6 with the syringe removed, showing the relation of the parts in the rotated position of the cap; Figs. 9, 10, and 11 are sections taken along the lines 9—9, 10—10, and 11—11, respectively, of Fig. 4 and Fig. 12 is a perspective view of the annular member seated under the upper shoulder of the syringe.

Referring more particularly to the drawings, the reference character 1 designates the outer cylindrical casing of the device which is to be held in the hand of the user and within which is concentrically arranged an inner hollow cylinder 2 adapted to receive a hypodermic syringe 3 of ordinary or special size and shape. The outer cylinder 1 is provided at its lower end with an external flanged portion 4 which enables the user to press the device firmly against the surface of the skin over the tissues within which the medicament is to be injected, such flange being prefera-

bly roughened at its outer edge to prevent slippage of the fingers of the user. The exterior surface of the cylinder 1 is also preferably roughened for the same reason. An inwardly extending flange 5 is provided at the upper end portion of the outer cylinder 1 for the purpose of guiding the movement of the inner cylindrical member 2 and to serve as a seat for the upper end of a coiled spring 6 which is positioned intermediate the outer and inner cylinders 1 and 2 and is concentrically arranged with relation thereto.

The inner cylinder 2 is provided at its lower end with an outwardly extending flange 7 having an outside diameter slightly less than the inside diameter of the outer cylindrical shell 1 so that it will readily move within the cylinder 1 and is adapted to serve as a seat for the lower end of the spring 6. Thus when the inner cylinder 2 is retracted from the outer cylinder 1, the spring 6 is compressed between the flanges 5 and 7 to yieldingly resist withdrawal of said inner cylinder 2 to its retracted position. The upper end portion of the inner cylinder 2 is provided with an enlarged annular portion or boss 8 which is adapted to seat the shoulder 9 on the upper end of the syringe 3. The external diameter of the boss is sufficiently greater than that of the inner cylinder 2 so that the under surface thereof forms a shoulder which operates as a stop to limit the downward stroke of the inner cylinder 2.

A releasable latch is pivotally mounted on the exterior surface of the cylinder 1 and operates to retain the inner cylinder 2 in its retracted position until the latch is moved to releasing position. The latch comprises a channel-shaped lever arm 11 which is pivotally mounted on the supporting brackets 12 positioned adjacent to the flanged portion 4 of the cylinder 1 and integral with the outer surface of such cylinder. The upper end of said lever arm is provided with an inwardly projecting portion 13 formed integral therewith which extends in through an aperture provided in the wall of the outer cylinder 1 and is adapted to engage with the under edge portion 45 of the flange 7 on the inner cylinder 2 when such cylinder is drawn to fully retracted position. The inner end of the portion 13 is preferably rounded to enable it to ride over the coils of the spring 6 without catching. Seated in an annular recess 14 formed on the interior side of the flanged portion 4 of the outer cylinder is a circularly shaped spring member 15 which is tensioned so that it bears outwardly against the inner wall of the recess. The free end portions of the spring are disposed on either side of the side flanges on the upper portion of the vertical arm 32, as shown in Fig. 9, such flanges limiting the rotational movement of the spring. As shown in Figs. 2 and 9, one of the free end portions of the spring 15 bears outwardly against the channeled sides of the lower portion of the lever arm 11 which extend through a slot 17 provided in the flanged portion 4 of the outer cylinder 1. With this arrangement the projecting portion 13 of the lever arm 11 is maintained in contact with the outer surface of the inner cylinder 2 when the parts are in normal position. When the inner cylinder 2 is withdrawn to its retracted position preparatory to the use of the device the spring 15 yieldingly resists any inward movement of the lower portion of the lever arm 11 caused by the projection 13 riding over the spring 6 and flange 7 of the inner cylinder and when the inner cylinder has been withdrawn to its fully retracted position the spring 75 rotates the lever arm 11 to position the projection

13 under the flange 7 of the inner cylinder, as shown in Fig. 2, thereby maintaining the inner cylinder in its retracted position until it is released by the user pivoting the lever arm 11 against the tension of spring 15. Projections 18 are integrally formed on each side of the lever arm 11 between the supporting brackets 12 and the flanged portion 4 of the outer cylinder and are adapted to engage the exterior surface of such cylinder and limit the inward movement of the lower portion of the lever arm. The outer surface of the lever 11 may be roughened in any suitable manner to provide a grip thereon for the user.

The syringe 3 comprises a barrel portion 18 provided with an integral collar or shoulder 9 at its upper end and an ejecting end 20 through which passes a discharge duct. Mounted on the ejecting end 20 is a needle hub 21 of the usual type provided with a needle 22. As shown in Fig. 1 the length of the barrel of the syringe and the length of the cylinders 1 and 2 are so related that a major portion of the syringe barrel extends below such cylinders when the parts are in normal or projected position. A scale 23 for indicating the amount of dosage is provided on the exterior surface of that portion of the syringe barrel which extends below the normally positioned cylinders 1 and 2. Thus by reason of this arrangement, the major portion of the syringe barrel is visible to the user when the needle has been projected into the patient and the visible scale enables the user to readily discharge the proper amount of medicament into the tissues penetrated by the needle without error.

A holder 24 is carried by the inner cylinder 2 for gripping and supporting the lower exposed portion of the syringe barrel, such holder comprising an upper cylindrical section 25 which is sweated or otherwise attached to the inner periphery of the inner cylinder 2 so that it is securely retained in position in said cylinder. The cylindrical section 25 is preferably of a length sufficient to solidly support the lower section 26 of the holder 24 which is integral therewith. The lower section 26 of the holder which is of a length substantially the same as that of the portion of the syringe barrel which extends below the inner cylinder 2, is disposed to the rear of the syringe barrel and is semi-circular in cross-section so that when the syringe barrel is positioned in said lower section 26, the latter does not interfere with the reading of the scale 23 on the syringe barrel.

The lower end portion of the section 26 is provided with two substantially parallel slots 27 which extend longitudinally of the section and separate the lower edge portions 28 of the section from the body portion thereof so that such edge portions are in the nature of longitudinally extending tongues or springs. The free ends of the lower edge portions or tongues 28 are provided with forwardly projecting arcuately shaped projections or toes 29 which are adapted to grip the syringe barrel as shown in Figs. 1 and 2. The free end portion of each tongue 28 and its associated toe 29 are turned inwardly adjacent their lower edges so that when the syringe is positioned in the device the tongues 28 are placed under a sufficient amount of tension to cause the free ends thereof and the toes 29 to securely hold the lower end of the syringe against transverse movement during the operation of the device. The lower edge portions of the tongues 28 and the toes 29 also seat against a shoulder 30 formed on the lower end of the syringe barrel and yieldingly

resists any upward movement of the syringe during the operation of the device.

Fixedly attached at its upper end to the outer surface of the cylinder 1 by the screws 31 is a vertically disposed arm 32. A portion of the flange 4 on the cylinder 1 is removed to enable the arm 32 to be positioned in parallel relation with the line of movement of the inner cylinder 2. A pair of forwardly projecting lugs 33 are integrally associated with the side edges of the vertical arm 32 and are positioned intermediate the lower end of the latter and the flange 4 on the cylinder 1. As shown in Figs. 1 to 3, the lugs 33 are curved away from each other at their outer end portions to form a seat or guide on which the lower section 26 of the holder 24 slides when it is moved up and down with the inner cylinder 2. The lugs 33 are positioned on the arm 32 so that the section 26 of the holder 24 remains in contact therewith throughout its range of movement. Fixedly secured to the inner side of the vertical arm 32 immediately above the guide lugs 33 is a pin 34 which is reduced in cross section adjacent its outer end so that a head portion 35 is formed thereon. The reduced portion of the pin 34 extends through a slot 36 provided in a longitudinally disposed raised portion 37 of the lower section 26 of the holder 24, such slot being of sufficient length to permit the holder 24 to be drawn to its fully retracted position with the inner cylinder 2. The head portion 35 of the pin rides on the edges of the slot within the raised portion 37 so that it does not engage with the barrel of the syringe during the movement of the latter in the operation of the device. With this arrangement, the lower section 26 of the holder 24 which tightly grips and supports the lower portion of the barrel of the syringe, is guided in its downward plunging motion by the guide lugs 33, pin 34 and slot 36 so that the needle of the syringe speeds straight to the fleshy area that is to be treated. Due to the fact that the guide lugs 33 prevent any rearward movement of the holder and the syringe 3 toward the arm 32, and the pin 34 together with the slot 36 prevent any rotative movement of the inner cylinder 2 and the holder 24 relative to the outer cylinder 1, and the head portion 35 of the pin prevents any movement of the syringe and the holder away from the arm 32, the syringe 3 is plunged downwardly under the influence of the spring 6 with a minimum of vibration of the syringe during such movement.

The lower end portion of the arm 32 is provided with forwardly extending side flanges 38 with which it is adapted to slidably receive the shank 39 of a foot 40. The foot 40 may be varied with reference to the needle 22 to control the latter's depth of penetration by loosening the nut 41 carried by the screw 42 which is fixedly mounted on the shank 39 as shown in Fig. 4, and moving the foot to the desired position. A longitudinally extending slot 43 in the lower end of the arm 32 enables the screw 42 to be moved with the shank 39 lengthwise of the arm 32. When the foot 40 has been moved to the desired position the nut 41 is tightened against the rear side of the arm 32 to hold the foot in the adjusted position. The upper end of the shank 39 is provided with a longitudinally extending slot 44 whereby the upper end of the shank is enabled to straddle the pin 34, the latter member operating as a stop to limit the upward adjustment of the foot 40.

The shoulder 9 at the upper end of the syringe barrel comprises two oppositely disposed straight-sided sections 47 and two oppositely disposed sections 48, the latter of which extend further from the axis of the syringe than the straight-sided sections 47. The straight-sided sections of the shoulder 9 are disposed to the front and rear of the syringe 3, the straight edge portion 49 of the forward section extending transversely to the longitudinally disposed scale 23 above such scale. The straight-sided sections 47 are used in connection with a clip 50 for braking the movement of the plunger 51, such clip consisting of an integral piece of resilient metal having a band portion 52 for embracing the upper portion of the barrel, spring fingers 53 which are flexed toward the axis of the barrel and are adapted to extend around the straight-sided portions of the shoulder 9, and terminal portions 54 adapted to contact with the outer surface of the plunger 51 and to brake its downward movement.

An annular member 56 of spring metal is seated in the boss 8 on the upper end of the inner cylinder 2 intermediate the seating face thereof and the shoulder 9 on the upper end of the syringe barrel, the external diameter of such annular member being approximately the same as the diameter of the inner wall of the boss so that the member 56 fits snugly within the boss. Integral with the outer peripheral edge of the annular disc are three small outwardly extending projections or lugs 57, 58, and 59, the lug 57 being diametrically opposed to the lugs 58 and 59 which are positioned relatively close to each other, as shown in Fig. 12. The lugs 57, 58, and 59 are adapted to be positioned in the apertures 60, 61, and 62, respectively, which are provided in the annular wall of the boss 8. As is clearly shown in Fig. 6, the aperture 60 which is adapted to receive the lug 57, is positioned in the front or forward portion of the annular wall of the boss 8 while the apertures 61 and 62 which are adapted to receive the lugs 58 and 59, respectively, are positioned in the rear portion of the annular wall of the boss. Thus it is seen that the annular member 56 can only be seated in the boss 8 in one position, namely with the lug 57 to the front of the device and lugs 58 and 59 to the rear of the device. This arrangement makes it possible to readily insert the syringe in the device so that it will be in its proper position for reading the scale 23 on the barrel thereof during the operation of the device as will be herein-after explained. While the annular member 56 is shown as being flat so that its entire undersurface seats on the seating face of the boss, it will be understood that the annular member 56 may be distorted or bent so that the two diametrically opposed portions of the annular member from which the projections extend seat on the boss while the remainder of the member is raised from the seating face thereof in bowed fashion. In this modified form, the annular member 56 is thus spring-tensioned against any downward movement of the shoulder 9 of the syringe which is seated on the raised portions thereof so that when the downward plunging motion of the inner cylinder 2 is abruptly stopped by the boss 8 contacting with the upper edge of the outer cylinder 1, the annular member 56 operates as a buffer or shock absorber to lessen the impact on the syringe 3 sufficiently to prevent any possibility of failure of the shoulder 9 thereof and minimizes vibration of the needle in the flesh of the patient. Integrally associated with

the inner edge portion of the annular member 56 and positioned on each side of the outwardly extending lugs 57 on said disc and equally spaced therefrom are two upwardly projecting resilient members 64 and 65 which are adapted to cooperate with one of the oppositely disposed straight-sided sections of the shoulder 9 to keep the syringe from turning during the operation of the device. As the annular member 56, by reason of the projecting lugs 57, 58, and 59 and the apertures 60, 61, and 62, can only be positioned in the boss 8 so that the members 64 and 65 are positioned adjacent the front portion of the annular wall of the boss and as such members 64 and 65 are closer to the axis of the syringe barrel than the outer edge portions of the sections 48 of the shoulder 9, the syringe can readily be inserted in position in the injector so that the scale thereof is in proper position for reading and the above-mentioned parts operate to maintain the syringe in this position. The annular member 56 is provided with diametrically opposed slots 66 through which the fingers 53 of the clip 50 pass, thereby enabling the shoulder 9 to seat on the annular disc 56. In the construction of the annular member illustrated, the members 64 and 65 are positioned adjacent the side edges of the forward slot.

Integrally associated with the annular member 56 and positioned intermediate the projections or fastening lugs 58 and 59 is an upwardly projecting spring member 67 which extends through a vertical slot 68 formed in the rear portion of the annular wall of the boss 8 so that its free end portion engages with the inner side surface of an annular locking ring or cover 69. (See Figs. 4, 6, and 8.) The free end portion of the spring member 67 bears with sufficient pressure against the inner side surface of the cover to prevent turning of the cover while the injector is in use. The top portion of the cover has an opening therein which is substantially the same shape as the top portion of the shoulder 9 on the syringe in order that the syringe may be positioned in or removed from the injector without removing the cover. When the syringe is to be inserted in the injector the cover is in the position shown in Fig. 7, so that the shoulder 9 of the syringe can be passed through the opening in the top portion of the cover and seated on the boss 8. When the syringe is in position in the injector the cover is positively turned through an angle of ninety degrees against the frictional resistance caused by the spring member 67 bearing against the inner side surface of the cover until the oppositely disposed widened portions 70 of the top of the cover are over the two oppositely disposed sections 48 of the shoulder 9 at the upper end of the syringe barrel, thereby locking the syringe in position in the barrel. To remove the syringe, the cover is rotated back through ninety degrees until the opening in the cover is positioned as shown in Fig. 7, with respect to the shoulder 9 on the syringe. The rotative movement of the cover for the above-mentioned purposes is definitely limited by means of stops as will be now explained. Punched or stamped from the material constituting the annular side wall of the cover are two tongues 71 and 72, the free ends of such tongues being disposed in opposite directions and extending inwardly a sufficient distance from the inner surface of the side wall of the cover to engage with an external groove 73 formed in the annular wall of the boss 8. The inner wall of

the groove is also provided with two tongues 74 and 75. The tongue 74 is disposed oppositely to the tongue 71 on the cover and extends outwardly in the groove a sufficient amount to engage with the tongue 71 to limit the rotative movement of the cover in a clockwise direction. 5 In a similar manner the tongue 75 is disposed oppositely to tongue 72 on the cover and cooperates with it to limit the rotative movement of the cover in a counter-clockwise direction. The sets of tongues or stops 71, 74 and 72, 75 are so 10 positioned with relation to each other that when the tongues 71 and 74 are in contact with each other, as shown in Fig. 6, the cover is in the position shown in Fig. 5 and locks the syringe 15 in place in the injector, and when the tongues 72 and 75 are in contact with each other, as shown in Fig. 8, the cover is in the position shown in Fig. 7 and enables the syringe to be removed from the injector. Thus the extent to which the 20 cover can be turned in either a clockwise or counter-clockwise direction is limited to ninety degrees. The inwardly projecting tongues 71 and 72 on the cover also cooperate with the groove 73 on the boss 8 to permanently maintain the 25 cover in place on the boss 8. The top edge 76 of the boss 8 is preferably beveled to enable the cover to be readily assembled on the boss, the tongues 71 and 72 readily sliding over such beveled edge into place in the groove 73 as the cover 30 is placed in position on the device.

In operating the injector, it is readily understood that the inner cylinder 2 is retracted to a position so that the inwardly projecting portion 13 of the lever 11 engages with the lower 35 side of the outwardly extending flange 7 on the lower end of the inner cylinder to hold the inner cylinder 2 in retracted position. When the foot 40 has been placed in position on the body of the patient, the lower end of the lever 11 is 40 pressed down, thereby releasing the inner cylinder 2 which plunges downward under the influence of the spring 6 to plunge the end of the needle 22 into the body of the patient to the desired depth. In their downward motion the 45 holder 24 and the syringe 3 are guided by the guiding lugs 33, the pin 34 including its flattened head 35 and the slot 36, such parts also operating to hold the holder 24 and syringe 3 sufficiently steady so that there is virtually no vibration 50 of the syringe barrel or the needle during such downward motion or at the end of their stroke.

While I have illustrated and described the preferred embodiment of the invention it will be 55 readily understood that various changes in the form, construction and arrangement of the various parts of the invention may be resorted to without departing from the scope of the invention, hence I do not wish to limit myself strictly 60 to the structure herein set forth.

I claim:

1. An automatic syringe injector comprising an outer hollow cylindrical member, an inner hollow cylindrical member positioned in said outer cylindrical member and adapted to reciprocate within the latter, a syringe having a flanged shoulder at its upper end extending through said inner cylindrical member, means provided on the outer end of said inner member for engaging the shoulder of the syringe to hold the syringe in position therein, said syringe being substantially greater in length than said cylindrical members so that a major portion of the syringe barrel projects below the lower edge portions of 70 75 80 85 90 95 100

- said members in the normal position of the latter, a graduated scale provided on the exposed projecting end portion of the syringe barrel intermediate the lower end of said barrel and the lower edge portions of said cylindrical members, a holding member secured at its upper end to said inner cylindrical member and extending longitudinally of the syringe to approximately the lower end of the syringe barrel, said holding member being so formed and so arranged with relation to the syringe barrel that it does not interfere with the reading of the graduated scale and being provided at its lower end with yieldable friction means adapted to grip the lower end portion of the syringe barrel, a spring for normally holding said cylindrical members one within the other and adapted to exert tension on the inner cylindrical member when the latter is retracted from said outer cylindrical member, and means for holding said inner cylindrical member in retracted position.
2. An automatic syringe injector comprising an outer hollow cylindrical member, an inner hollow cylindrical member positioned in said outer cylindrical member and adapted to reciprocate within the latter, said inner cylindrical member being adapted to receive and support the barrel of a syringe, a spring for normally holding said cylindrical members one within the other and adapted to exert tension on the inner cylindrical member when the latter is retracted from said outer cylindrical member, means for holding said inner cylindrical member in retracted position, said means comprising an aperture in the wall of said outer cylindrical member, a lever pivotally supported on said outer cylindrical member and having an inwardly projecting portion adapted to project through the aperture in said outer cylindrical member and engage with said inner cylindrical member to hold the latter in retracted position, an annular groove formed in the interior surface of said outer cylindrical member, a circularly formed spring positioned in said annular groove and an opening in the wall of said outer cylindrical member to enable a free end portion of said spring to engage said lever and normally hold the projecting portion thereof against the exterior wall of said inner cylindrical member.
3. An automatic syringe injector such as defined in claim 1 in which the holding member is provided at its lower end with a plurality of longitudinally extending tongues, the lower end portions of said tongues being adapted to tightly grip the lower portion of the projecting syringe barrel.
4. An automatic syringe such as defined in claim 1 in which the holding member comprises an upper tubular portion securely supported on the inner wall of said inner cylindrical member and a lower portion integral with said upper portion and positioned exteriorly of said cylindrical member and adjacent to the outer surface of the syringe barrel, said lower portion being slotted at its lower end to form a plurality of longitudinally extending tongues, the lower ends of said tongues being bent inwardly to frictionally engage with the lower portion of the syringe barrel.
5. An automatic syringe injector comprising an outer hollow cylindrical member, an inner hollow cylindrical member positioned within said outer cylindrical member and adapted to reciprocate within the latter, a syringe supported at its upper end portion within said inner cylindrical member,
- said syringe being substantially greater in length than said cylindrical members so that a major portion of the syringe barrel projects below the lower edge portion of said members in the normal position of the latter, a graduated scale provided on the exposed projecting end portion of the syringe barrel intermediate the lower end of said barrel and the lower edge portions of said cylindrical members, a holding member extending longitudinally of the syringe and mounted at its upper end on the inner cylindrical member, said holding member being adapted to removably grip the lower portion of the syringe, means carried by the outer cylindrical member adapted to guide the movement of said longitudinal holding member, a spring for normally holding said cylindrical members one within the other and adapted to exert tension on the inner cylindrical member when the latter is retracted from said outer cylindrical member, and means for holding said inner cylindrical member in retracted position.
6. An automatic syringe injector such as defined in claim 5 in which the means carried by the outer cylindrical member for guiding the movement of said longitudinal member comprises an arm extending longitudinally of the syringe in parallel relation with said longitudinal member and securely fastened at its upper end to said outer cylindrical member, said arm having a pair of guide lugs adapted to slidably engage with the exterior surface of said longitudinal member throughout its range of movement and to prevent movement of said longitudinal member toward said arm.
7. An automatic syringe injector such as defined in claim 5 in which the longitudinal member is semi-circular in cross-section and the means carried by the outer cylindrical member for guiding the movement of said member comprises an arm extending longitudinally of the syringe in parallel relation with said longitudinal member and securely fastened at its upper end to said outer cylindrical member, a pair of guide lugs integral with said arm and adapted to slidably engage with the exterior surface of said longitudinal member throughout its range of movement, the engaging portions of said extensions being arcuately shaped so as to form a cradle for the semi-circular outer surface of said longitudinal member and prevent movement of said longitudinal member toward said arm.
8. An automatic syringe injector such as defined in claim 5 in which said holding member is provided with a longitudinal slot and the means carried by the outer cylindrical member for guiding the movement of said holding member comprises an arm extending longitudinally of the syringe in parallel relation with said longitudinal member and securely fastened at its upper end to said outer cylindrical member, said arm carrying a guide adapted to engage with said longitudinal slot.
9. An automatic syringe injector such as defined in claim 5 in which said holding member is provided with a longitudinal slot and the means carried by the outer cylindrical member for guiding the movement of said holding member comprises an arm extending longitudinally of the syringe in parallel relation with said longitudinal member and securely fastened at its upper end to said outer cylindrical member, said arm carrying a pin extending through said slot and adapted to prevent rotative movement of said longitudinal member and said inner cylindrical member relative to said outer cylindrical member, said

pin having a head portion adapted to engage with the side portions of the slot and prevent movement of said longitudinal member away from said arm.

5 10. An automatic syringe injector such as defined in claim 5 in which said holding member is provided with a longitudinal slot and the means carried by the outer cylindrical member for guiding the movement of said holding member comprises an arm extending longitudinally of the 10 syringe in parallel relation with said longitudinal member and securely fastened at its upper end to said outer cylindrical member, means carried by said arm and adapted to engage with said slot to prevent rotative movement of said holding member, means carried by said arm adapted to slidably engage with one side of said holding member to prevent movement of the latter in one direction, and means carried by said arm adapted to slidably engage with the opposite side of said holding member to prevent movement of the latter in the opposite direction, all of said parts co-operating to prevent vibration of said holding member and said syringe in their downward plunging motion and to guide the needle straight to the place to be penetrated.

11. An automatic syringe injector comprising an outer hollow cylindrical member, an inner hollow cylindrical member positioned within said outer cylindrical member and adapted to reciprocate within the latter, said inner member having an expanded annular portion at the upper end thereof adapted to seat on the upper edge portion of said outer member, a syringe having a flanged shoulder at its upper end adapted to seat in said expanded annular portion, said syringe being substantially greater in length than said cylindrical members so that the major portion of the syringe barrel projects below the lower edge portions of said members in the normal position of the latter, a graduated scale provided on the exposed projecting end portion of the syringe barrel intermediate the lower end of said barrel and the lower edge portions of said cylindrical members, means associated with the expanded annular portion of the inner cylindrical member and the shoulder on said syringe to operate as a positioning means for the syringe, a spring for normally holding said cylindrical members one within the other and adapted to exert tension on the inner cylindrical member when the latter is retracted from said outer cylindrical member, and means for holding said inner cylindrical member in retracted position.

12. An automatic syringe injector such as defined in claim 11 in which said positioning means comprises an annular member positioned intermediate the seating face of said expanded annular portion and the shoulder on said syringe and having an upwardly projecting extension adapted to engage with a predetermined portion of the syringe shoulder, and means for locking said annular member in a predetermined position in the seat of said expanded annular portion whereby the position of the syringe shoulder is fixed with respect to the expanded annular portion of the injector.

13. An automatic syringe injector such as defined in claim 11 in which said positioning means comprises an annular disc positioned intermediate the seating face of said expanded annular portion and the shoulder on said syringe and having an upwardly projecting extension adapted to engage with a predetermined position of the syringe shoulder, a plurality of projections ex-

tending outwardly from the peripheral edge of said annular disc, and an equal number of apertures in the annular wall of said expanded portion adapted to receive said projections whereby the position of the syringe shoulder is fixed with respect to the expanded annular portion of the injector, said projections and apertures being so positioned relative to the upstanding projecting extension of the annular disc that when said extension is in engagement with the syringe shoulder the syringe is secured in the injector with the graduated scale thereon in proper position for reading.

14. An automatic syringe injector comprising an outer cylindrical member, an inner hollow cylindrical member positioned within said outer cylindrical member and adapted to reciprocate within the latter, said inner member having an expanded annular portion at the upper end thereof adapted to seat on the upper edge portion of said outer member, a syringe having a flanged shoulder at its upper end adapted to seat in said expanded annular portion, said shoulder having at least one edge portion which is positioned at a different distance from the axis of the syringe than the remaining edge portion thereof, a cover rotatably mounted on the annular wall of said expanded annular portion and permanently secured thereto, said cover having an opening which is so formed relative to the syringe shoulder, that in one position of the cover the syringe is securely held in said injector, while in another position of said cover the syringe may be removed from the injector, a spring for normally holding said cylindrical members one within the other and adapted to exert tension on the inner cylindrical member when the latter is retracted from said outer cylinder, and means for holding said inner cylindrical member in retracted position.

15. An automatic syringe such as defined in claim 14 in which the expanded annular portion is provided with a slot in the annular wall thereof, and an annular disc member positioned intermediate the seating face of said expanded annular portion and the shoulder on said syringe and having an upwardly projecting extension integral therewith, said extension projecting through the slot provided in the wall of the expanded annular portion and frictionally engaging with the side wall of said cover to prevent free rotation of the cover.

16. An automatic syringe such as defined in claim 14 in which the expanded annular portion is provided with an external annular groove and a member extending from the inner surface of the side wall of the cover and engaging with said groove to permanently secure the cover on said expanded annular portion while enabling rotational movement thereof.

17. An automatic syringe such as defined in claim 14 in which the expanded annular portion is provided with an external annular groove, a pair of spaced members extending from the inner surface of the side wall of the cover and engaging with the groove to permanently secure the cover on said expanded annular portion while enabling rotational movement of said cover, and means cooperating with said spaced members for limiting the rotational movement of said cover.

18. An automatic syringe injector comprising an outer hollow cylindrical member, an inner hollow cylindrical member positioned within said outer cylindrical member and adapted to recipro-

cate within the latter, a syringe supported at its upper end portion within said inner cylindrical member, said syringe being substantially greater in length than said cylindrical members so that a major portion of the syringe barrel projects below the lower edge portion of said members in the normal position of the latter, a graduated scale provided on the exposed projecting end portion of the syringe barrel intermediate the lower end of said barrel and the lower edge portions of said cylindrical members, said syringe having an outwardly extending portion formed on the lower projecting portion of the syringe barrel, a holding member extending longitudinally of the syringe and mounted at its upper end on the inner cylindrical member, said holding member being provided at its lower end with a yieldable gripping means adapted to cooperate with the lower portion of the syringe and the outwardly extending portion formed on said syringe to prevent displacement of the syringe during the operation of the device, a spring for normally holding said cylindrical members one within the other and adapted to exert tension on the inner cylindrical member when the latter is retracted from said outer cylindrical member and means for holding said inner cylindrical member in retracted position.

FAIRLEIGH S. DICKINSON. 15
